CLAIM

I claim the ornamental design for a pet feeder toy, as shown and described.

DESCRIPTION

FIG. 1 is a perspective view of a pet feeder toy, showing my new design;

FIG. 2 is a top plan view thereof;

FIG. 3 is a side elevational view thereof; and,

FIG. 4 is a side elevational view thereof, rotated 180 degrees from the view shown in FIG. 3.

The appearance of the bottom surface of the pet feeder toy is not claimed.
